UNITED STATES PATENT OFFICE.

RUDOLPH WELCKER, OF SPRINGFIELD, MASSACHUSETTS, ASSIGNOR OF ONE-FOURTH
TO FRANKLIN G. NEAL, OF SPRINGFIELD, MASSACHUSETTS.

PRESSURE-OPERATED VALVE APPARATUS.

Application filed December 29, 1924. Serial No. 758,674.

This invention is an improvement in the means for operating valves as embodied in a pressure operated valve apparatus. One specific and important embodiment of the invention is in the improved means for storing and releasing a liquid by a valve controlled apparatus of improved construction. This embodiment of the invention particularly designed for storing and releasing a liquid as in a flush tank, is illustrated by the drawings and following description.

In the drawings:

Fig. 1 is a vertical sectional view of a storage tank designed as a flush tank embodying the invention in one preferred form;

Fig. 2 is a detail sectional view of the tank showing the main valve of Fig. 1 in open position.

One preferred form of the invention chosen for purposes of illustration relates to a flush tank. The tank 1 may be of any suitable shape as round or rectangular, but due to the features of the invention which will appear it may be of smaller volume than flush tanks of the prior art usually are for the same work. The tank 1 shown may be considered round in horizontal cross section for simplicity in construction.

A bottom casting 2 and a top casting 3 form air tight closures for tank 1. A fluid inlet 4 and a drain outlet 5 each provided with a convenient hand valve 4' and 5' respectively are connected to the bottom casting 2. A large vertically disposed flushing outlet pipe 6 is mounted in the center of the bottom casting 2 and has its top end open and spaced a short distance below the casting 3. Depending from the casting 3 and concentric with pipe 6, but large enough to establish an annular space 7, is a pipe section 8 which has its bottom end open and spaced a short distance above the casting 2. The top end of pipe 8 is closed by the casting 3 at the center portion of which is a valve controlled air outlet port or ports 10 normally closed by valve 11 as will be described. On the top of outlet pipe 6 is a circular cap valve 12 designed to close and open the top end of this pipe and to moveably slide from closed or open position while in good sliding contact as a piston within the pipe section 8.

The valve 12 is shown in closed position in Fig. 1 and in open position in Fig. 2. It is

circular to fit pipe section 8 with extensions above and below the crown designed for closing pipe 6. The top of the latter is provided in any suitable manner with a good valve seat designed to take a reversely arranged seat in the valve as indicated.

An air port 13 is provided through the valve casting 12 to connect the space above valve 12 with the annular space 7 between pipe sections 6 and 8. A second air port 14 is provided through the valve casting to connect the annular space 7 with the space above the liquid in tank 1, outside of pipe 8. As shown, this port 14 when the valve is closed, registers with a port 15 in pipe 8. In the annular space 7, I preferably provide a rather loose float ring 16 with a suitable packing at the top so that the ports 13 and 14 are closed when the liquid fills the space 7, and so that this liquid will have no substantial access through port 13. The port 14 is also closed when the valve 12 is open for the ports 14 and 15 are not then in registering position. A circumferential, horizontal groove in the valve casting at the top level of port 14 permits port 15 to register with port 14 even though the latter turns in its up and down movements.

The air valve 11 may be of any suitable construction operable to admit and shut off the passage of air through air ports 10 from and to the space A within pipe 8 above main valve 12. As shown the air valve 11 is a simple form of disk valve held upwardly against its seat with an air tight closure by means of a spring surrounding the valve stem and bearing against casting 3 and a shoulder of the valve stem. Any air pressure in space A will assist in holding air valve 11 closed. The closing spring for the valve is preferably made so that it will permit air valve 11 to open, if and when there is a tendency toward a vacuum in space A as the apparatus works. The air ports 10 and the opening surrounding the valve stem provide access of atmospheric pressure to the top of valve 11 over a considerable area so that with the spring strong enough to normally close the valve when the air pressure in space A is equal to or greater than atmospheric pressure, valve 11 will open when the air pressure in space A is reduced slightly below atmospheric pressure and this action will be permitted if the valve spring is not too strong. Other types of air valves and arrangements

are available to accomplish my purpose at this point which is to normally retain air pressure in space A, releasing it only when desired, as by pressing the air valve stem 5 against the spring, and to automatically admit air to space A when there is a tendency toward a vacuum in this space as will be set forth.

With the apparatus constructed as described, its operation as a flush tank will now be described. The tank is placed in position with all valves normally closed. When the inlet valve 4 is opened to admit water under pressure from pipe 4' as from the city water system, the tank rapidly fills until the confined air is put under sufficient pressure at the top of the tank to balance the water pressure in the feed pipe, which will occur because the tank is normally air tight and in this respect operates like an air bell to prevent the water from filling it completely. The feeding operation then stops although the feed inlet is still open and normally remains open at all times. In this condition, the air which originally filled the tank at atmospheric pressure has now been forced under pressure to the top of the tank. Due to ports 13, 14 and 15 the air has free circulation above the liquid and therefore is put under the same pressure above the valve 12 in space A as it is above the water in the tank and outside of pipe 8 in space B. The float ring 16 rises with the water to close ports 13 and 14. The water has then risen substantially to its high level, but the outlet valve 12 is preferably still above this level. The float ring is used as a precautionary means to prevent the water from spouting up above the valve and into space A. In this described condition of the apparatus, the air pressure on the outlet side of the valve 12 is at atmospheric pressure while the pressure above the valve 12 is substantially above atmospheric pressure. This fact gives a substantial pressure acting to hold the valve closed. The valve seat is above the water level because it is preferably located to be in the air space of the tank at all times, so that during the storage period 50 the valve is dry and not subjected to possible chemical action of impure water.

The water may be thus stored in the tank until needed and under the best conditions with respect to safeguarding the flush valve. When it is desired to empty the tank the control or air valve 11 is opened by pressing downwardly on the valve stem. The air pressure above the valve 12 within pipe section 8, or space A is now released down to atmospheric pressure while the pressure above the water outside of pipe section 8 or in space B is still maintained. This pressure causes an immediate lifting of the valve 12 as the pressure in the annular space 7 can act to relieve itself upwardly against the

weight of the valve 12 alone. The valve 12 then takes the position shown in Fig. 2 where it no longer closes the top of pipe 6 and the annular space 7. A siphon action is thus established from the annular space B outside pipe 8 up the annular space 7 and down the outlet pipe 6. The siphon action alone would then empty the tank but it is one desirable feature of the invention that such action is started with a rush under the substantial air pressure exerted to release itself from the confined space B above the main body of water. This pressure continues to act and forces the water out of the tank with much greater pressure at the beginning when the flushing action is most needed and with a gradually lessening pressure until the siphon action is broken when the water level in the tank falls to the open edge of pipe 8.

During the time the water is being stored and while the siphon action is emptying the tank, the water inlet is open so the volume of water emptied is increased by the amount permitted to enter from the inlet as the air pressure is being relieved. But as soon as the siphon is broken, as it automatically is, when the water level reaches the bottom of pipe 8, the incoming water starts again to fill the tank to again compress the air and tighten the valve 12 which falls on its seat upon the breaking of the siphon. The water supply, therefore, automatically reestablishes the equilibrium of pressure between the water and air in the tank and the air pressure holds the outlet valve 12 closed while the water inlet 4 remains open.

Since the opening of the air valve 11 releases some of the air in the tank, each time the siphon is established, a new supply needs to be furnished to space A. This may be accomplished in many ways as by an automatically controlled air inlet separate from valve 11 to admit air to tank 1 whenever its air pressure falls below atmosphere. As shown and described for purposes of simplification, this function is performed through valve 11. As the last of the siphoned water is leaving outlet pipe 6 there is a suction created as by a piston in pipe 6 to lower the air pressure in space A. The float ring 16 drops down with the water in annular space 7 with a like action. Valve 12 is sucked to a tightly closed position, but the suction has been created and continues so that the pressure in space A is lowered and valve 11 automatically opens as described previously to establish substantially atmospheric pressure in said space. As the water level rises in tank 1 due to the still open inlet 4, the air pressure is increased in space B and in space A since there is a connection through ports 15, 14, 13 when the valve 12 is closed and the water is also rising in annular space 7. The air pressures in spaces A and B are

equalized, valve 11 is closed by the increasing air pressure as well as by its spring. The tank 1 refills automatically and stands ready to be again flushed in the same manner as described.

The drain pipe 5 is of course normally closed in the operation of the apparatus. The valves 4' and 5' immediately adjacent the flush tank are accessories of considerably 10 convenience even though the former is open for the most part and the latter is closed. If the tank is to be left unused over any considerable period of time, valve 4' may be closed and valve 5' opened to leave the apparatus drained and in dry condition. If 15 the air valve 11 should happen to be held open while the tank filled with water, the desired air supply in the tank would be depleted. But whatever happens in this or 20 like unusual situations, the whole apparatus can be readily put back in the right condition. The valve 4' may be closed while all water is drained from the tank through pipe 5 which empties into pipe 6. Then valve 11 25 may be opened to make sure that atmospheric air pressure obtains in the empty tank (although valve 11 should open automatically for this purpose). By now starting the use 30 of the apparatus, as in the case of its original installation, opening valve 4' and closing valve 5', everything is sure to be put in proper working condition.

As previously mentioned, it is desirable to have the opening of pipe 6 above the normal water level of the water stored in the tank. This can be readily determined by and 35 in relation to the pressure of the liquid from inlet pipe 4'. The higher this pressure is the higher pipe 6 must be made to be above the level where the air pressure stops the further feed of liquid through the open inlet.

I have not attempted to show all the available safeguards in making the valve 12 seat on the top of pipe 6 so as to prevent any 40 insidious leaking at this point. Such valve devices are known and constitute a simple engineering problem. I might mention, however, that it may be desirable to have a cone shaped valve surface of yielding material 45 as water proof leather or rubber to rest on the valve seat of pipe 6 so that any specks of foreign matter may sink into the valve which may be of the self centering type. And such precautions thus indicated in a 50 general way to insure that my tank is made air tight and water tight are all within the obvious engineering knowledge which may be applied to the practice of my invention.

I have described the invention in its simple 55 form to best bring out its principles and one preferred embodiment without the confusion of engineering details.

I believe I am the first to invent a pressure operated valve apparatus having all or 60 some of the advantages of that described. I

desire to claim my invention in its various aspects as broadly as the law allows.

What I claim is:

1. A pressure operated valve apparatus comprising a tank, an outlet pipe extending through the bottom of the tank and with its upper end spaced a short distance from the top of the tank, a second pipe extending from the top of the tank and with its lower end spaced a short distance from the bottom of the tank, said second pipe being arranged concentrically with the outlet pipe and in spaced apart relation to form an annular passage from the bottom part of the tank up to the top opening in the outlet pipe, a piston valve mounted in the second pipe and adapted to open and close said opening in the outlet pipe, and means to create a pressure in the top of said tank within and without said second pipe and means to release the pressure within said pipe above said piston valve to thereby open the valve and establish a siphonic action from the tank through said outlet pipe. 75

2. A pressure operated valve apparatus comprising a tank, a siphon outlet means for the tank, a valve for said means normally above the liquid level in the tank and operable solely by fluid pressure, and devices operable from without the tank to create one 90 pressure condition within the tank to hold said valve closed or a different pressure condition within the tank to open said valve and put the siphon outlet means in operation. 95

3. A flush tank having a normally open inlet passage and a normally closed outlet passage having its entrance located above the bottom of the tank, means to control the outlet passage comprising a valve apparatus at the entrance of the outlet passage operable by air pressure created by the fluid entering through said inlet and means operable from without said air tank to apply said pressure to operate said valve apparatus when desired. 100

4. A flush tank comprising an air tight fluid storage container having a normally open inlet passage for fluid under pressure and by which air pressure is established in the tank, a normally closed outlet passage 105 with its entrance located above the bottom of the tank and of larger capacity than the inlet passage and operable to empty the tank, and means controlled from without the tank to apply the air pressure in the tank for opening said outlet passage to empty the tank. 115

5. A flush tank comprising an air tight fluid storage container having a normally open inlet passage for fluid under pressure, a normally closed outlet passage forming one leg of a siphon of larger capacity than the inlet passage to empty the tank, a siphon structure with one leg forming said outlet passage, having a closure at the top of 120 125 130

- such leg, and with a second leg having an inlet near the bottom of the tank and means controlled from without the tank for opening said outlet passage to establish siphonic action through said structure and to empty the tank, said means being arranged to automatically close the outlet passage when the tank is substantially empty.
6. A flush tank comprising an air tight fluid storage container having a normally open inlet passage for liquid under pressure and arranged to compress the air in the tank above the liquid, and an outlet passage of larger capacity than the inlet passage, a valve arranged to normally close said outlet passage at a point above the liquid level and means controlled from without the tank to release the air pressure above the valve and cause the pressure above the liquid acting alone to open the valve and force the liquid to the outlet until the tank is emptied and then close the valve.
7. A flush tank comprising an air tight container for liquid, a normally closed air valve for the container, a normally open liquid inlet to the container, a siphon apparatus to empty the container, all constructed and arranged to establish air pressure within the container capable of starting the siphon apparatus and to control said pressure for such purpose through said air valve.
8. The combination of an air tight tank for liquid arranged to be normally in open communication with a source of liquid under pressure, a siphon apparatus having an outlet valve above the normal liquid level of the tank and arranged to empty said tank, and means operable from without the tank to start the operation of said apparatus solely by the fluid pressure therein.
9. The combination of an air tight tank for liquid arranged to be normally in open communication with a source of liquid under pressure, a siphon apparatus having an outlet valve above the normal liquid level of the tank and arranged to empty said tank, and means operable from without the tank to start the operation of said apparatus solely by the fluid pressure therein, said apparatus being constructed and arranged to automatically stop the siphonic action while liquid is still entering said tank.
10. A pressure operated flush tank comprising an air tight liquid container arranged to have normally open communication with a source of liquid under pressure whereby air pressure is created above the liquid in the tank to shut off a continuous liquid feed, means to empty said tank including a valve located above the normal liquid level in the tank and operable solely by pressure changes in the tank and means operable from without the tank to effect such pressure changes.
11. The combination of a tank with an inlet at the bottom, an outlet pipe with an opening near the top, a hood extending in spaced relation over the outlet pipe and with its open end near the bottom of the tank, a valve at the top of the outlet pipe and an air valve operable to control the air pressure in the top of said hood.
12. The combination of a tank with a liquid inlet near the bottom, an outlet pipe extending through the bottom to a point near the top of the tank, a cylinder closed at the top of the tank and extending in spaced relation over the outlet pipe to a point near the bottom, a piston valve slidable in said cylinder and adapted to close the top of said outlet pipe, an air valve between the top of the hood and the atmosphere, an air port through said piston valve between the top of the cylinder and the annular space between the cylinder and the outlet pipe, and air port through said piston valve between said annular space and registering with a port through the cylinder when the piston valve is in closed position.
13. The combination of an air tight tank, an inlet pipe for liquid, an outlet pipe and means to establish a siphon action through the outlet pipe by the pressure created by liquid entering the inlet pipe, an air valve for the tank to control said pressure and establish the siphon action.
14. The combination of a closed tank having an inlet for fluid under pressure, a siphon apparatus within said tank including a pressure operated valve between the two legs of the apparatus, an air valve to control the flow of air between the space on one side of the valve and the outside of the tank, said air valve being operable to release pressure on one side of the siphon valve to start the siphon action and automatically operable to prevent any substantial vacuum on that side of the valve as the siphon apparatus works to empty the tank.
15. The combination of a closed tank arranged to be in normally open communication with a source of liquid under pressure, a siphon apparatus having an outlet valve above the normal liquid level within the tank and operable to empty it when desired solely by the action of the air pressure in the tank created by the liquid constantly tending to fill the tank, and means to replenish the air supply to said tank and control the air pressure in the tank to thus control said siphon.
16. The combination of a closed tank adapted to be in normal open communication with a source of liquid under pressure, a siphon apparatus having an outlet valve above the normal liquid level within the tank and operable to empty it when desired, and means to put said apparatus into action, said means being arranged to control the air

pressure above the liquid in the tank and within the siphon apparatus to work the outlet valve solely by fluid pressure.

17. The combination of a closed tank, an inlet pipe for liquid under pressure, an outlet pipe extending through the bottom of the tank and opening near the top of the tank, a cylinder of larger diameter depending from the top of the tank over the outlet pipe to a point near the bottom of the tank, a piston fitted to slide in said cylinder and serve as a valve for the outlet pipe, an air valve for the tank between the top of the cylinder and the atmosphere, air ports through the piston to connect the space thereabove, the annular space formed by the outlet pipe and cylinder, and the latter with the space above the liquid outside of the cylinder, an air port through the cylinder to make said last named connection only when the piston closes the outlet pipe, a float ring serving to close said air ports when the annular space is full of liquid and the outlet pipe closed.

25 18. The combination of a closed tank, an inlet pipe for liquid under pressure, an outlet pipe extending through the bottom of the tank and opening near the top of the tank, a cylinder of larger diameter depending from the top of the tank over the outlet pipe to a point near the bottom of the tank, a piston fitted to slide in said cylinder and serve as a valve for the outlet pipe, an air valve for the tank between the top of the cylinder and the atmosphere, air ports through the piston to connect the space thereabove, the annular space formed by the outlet pipe and cylinder, and the latter with the space above the liquid outside of the cylinder, an air port through the cylinder to make said last named connection only when the piston closes the outlet pipe, a float ring serving to close said air ports when the annular space is full of liquid and the outlet pipe closed, and a normally closed drain pipe with a valve therein.

20 19. A flush tank comprising a cylinder closed at top and bottom by header members, an inlet pipe for connection to a water supply under pressure, a valve in said pipe, an outlet pipe extending through the bottom header member to a point near the top header member, a pipe or cylinder extend-

ing from the top header member in spaced relation but concentric with the outlet pipe to a point near the lower header member, a piston mounted to slide in said cylinder and serve as a lift or check valve for the outlet pipe, an air valve controlling a port between the space in said cylinder above the piston and the atmosphere.

20. A flush tank comprising a cylinder closed at top and bottom by header members, an inlet pipe for connection to a water supply under pressure, a valve in said pipe, an outlet pipe extending through the bottom header member to a point near the top header member, a pipe or cylinder extending from the top header member in spaced relation but concentric with the outlet pipe to a point near the lower header member, a piston mounted to slide in said cylinder and serve as a lift or check valve for the outlet pipe, an air valve controlling a port between the space in said cylinder above the piston and the atmosphere, and a second valved outlet pipe with an opening at the bottom header member.

21. A flush tank comprising an air tight tank, an inlet pipe for fluid under pressure, a normally open valve in said pipe, an outlet pipe of larger capacity than the inlet pipe and having its end within the tank located above the normal liquid level in the tank determined by the degree to which the fluid pressure can compress the normal air volume of the tank when empty above the liquid therein when full, a normally closed valve for said outlet pipe, and means to open said valve and force the liquid to the opening of the outlet pipe, said means being operable to lower the air pressure above said valve while maintaining the air pressure above the liquid in the tank over an area surrounding said valve.

22. A flush tank having a normally open inlet passage tending to feed water below the liquid level in the tank at all times and a normally closed outlet pipe, a valve for said pipe located above the normal liquid level in the tank and operable to be opened solely by siphonic action and means to effect such action when desired.

In testimony whereof I have affixed my signature.

RUDOLPH WELCKER.
